UNITED STATES PATENT OFFICE

MERTON W. HOWARD, OF LYNN, MASSACHUSETTS, ASSIGNOR TO HOWARD DEVELOPMENT COMPANY, OF LYNN, MASSACHUSETTS, A CORPORATION OF MASSACHUSETTS

EDGE SETTING MACHINE

Application filed January 12, 1929. Serial No. 332,126.

This invention relates to edge setting machines, and especially, although not exclusively, to machines for setting the edges of toplifts attached to the heels of boots and 5 shoes.

The invention has for its general object to provide an automatic machine for rapidly and accurately performing all of the required operations upon the edge of an attached toplift or the like, said machine being capable of 10 rapid operation and of a relatively large output of high-grade work of even quality with a minimum of skilled attendance, and being adjustable to adapt the same to work of a wide 15 variety of shapes and sizes.

The operation of setting the edge of an attached toplift has for its objects to finish and polish the raw edge of a toplift which has been previously inked and waxed, to roll in 20 the joint between the toplift and the heel so as to close said joint and make the surfaces of the heel and toplift smooth and continuous, and to mold the edge of the toplift so as 25 to form thereon a projecting circumferential bead, a suitably shaped "bed", or surface between the bead and the heel proper, and a portion known as the "panel" at the outer side of the bead, which last-named portion is subsequently buffed off in the final finishing of 30 the toplift to bring the bead flush with the outer surface. These operations are usually performed by a heated iron having a configuration substantially complementary to the desired configuration of the bed, bead and 35 panel, and which is so manipulated with reference to the edge in question as to produce the several results above referred to. The satisfactory performance of these operations necessitates the proper fulfillment of a number 40 of requirements. In the first place, the pressure of the iron upon the edge of the toplift tends to upset the material of the latter, which results in what is known as "pouting" or "cupping" of the toplift, that is to say, a 45 spreading of the material at the panel portion of the edge which causes the free outer face of the toplift to assume a more or less concave form. Since the purpose of forming the panel is to leave room for subsequent 50 buffing of the outer face without cutting into

the bead, if said outer face has assumed a concave form, the buffing necessary to restore it to its plane form may be sufficient to destroy the bead notwithstanding the provision of the panel. In order to avoid pouting or 55 cupping it is necessary to shape and manipulate the iron in such a manner as to exert a pressure heightwise of the heel against the outer face of the toplift sufficient to offset this tendency. In addition to the manipulation 60 of the iron necessary to prevent pouting and its relative movement circumferentially of the toplift edge, said iron must also be rocked toward the heel to roll in the joint between the latter and the toplift. Furthermore, the 65 relative movement of the iron and toplift in order to cause the former to travel circumferentially of the latter must be about an axis which is accurately perpendicular to the plane of the bottom face of the toplift in 70 order that the resulting bead may be accurately parallel to said bottom face.

In edge setting machines as heretofore constructed the foregoing operations have all depended to a large extent upon the skill of the 75 operator and have been slow and laborious. Moreover, they have usually been accomplished by short, repeated, local strokes of the iron, whereas for the best results and to prevent uneven heating, long, even strokes 80 extended about the entire circumferential portion of the edge to be finished are desirable.

The present invention has for an object to provide a machine in which the several factors above referred to are definitely predetermined, by suitable adjustments in accordance with the particular work being operated upon, without further attention on the part of the operator, whose sole duty thereafter consists 85 in inserting and removing the work, the operation of the machine with a given set-up being otherwise wholly automatic. Another object of the invention is the provision of a machine of this character in which the edge 90 setting strokes are long and continuous from end to end of the surface to be finished, and whose speed of operation, and consequent output, is greatly increased over machines of 95 like purpose as heretofore used. 129

To these ends a machine embodying the invention in its preferred form includes an edge setting iron; a jack or work holder having means for automatically positioning a heel with its attached toplift in proper relation to the iron, said positioning means being adjustable in accordance with the particular work being operated upon; power operated means for oscillating said jack with the work therein in contact with the iron, the amplitude of oscillation being such, determined by suitable adjustment, as to cause the full length of the edge surface to be finished to be traversed by the iron at each oscillation; automatic means for operating the iron during the oscillation of the jack to cause the same to roll in the joint between the toplift and the heel, said means being adjustable to vary the movement of the iron in accordance with requirements; means for interrupting the oscillation of the jack after a predetermined number of strokes, for operating said jack to release the work, and for withdrawing the iron therefrom in order to permit the finished work to be removed and new work to be inserted, and for thereafter causing the jack to clamp the work, the iron to be applied thereto, and the oscillation of the jack to be resumed; means for automatically controlling the pressure applied by the iron to the work; and means for so supporting the iron that a portion of its pressure against the edge of the toplift is converted into a pressure heightwise of the heel to prevent pouting.

The foregoing and other objects and features of the invention, together with means whereby the latter may be carried into effect, will best be understood from the following description of a preferred embodiment thereof illustrated in the accompanying drawings. It will be recognized, however, that the particular construction described and shown has been chosen for purposes of exemplification merely, and that said invention, as defined by the claims hereto appended, may be otherwise embodied without departure from the spirit and scope thereof.

In said drawings:

Fig. 1 is a front elevation of the complete machine.

Fig. 2 is a plan view thereof.

Figs. 3 and 4 are left and right end elevations respectively.

Fig. 5 is a detail plan view, partly broken away, of the work clamping means, illustrating the positioning of the work therein.

Fig. 6 is an enlarged detail plan view partly in section of the means for holding and operating the iron, showing the latter in its normal position.

Fig. 7 is a similar view showing the iron in its rocked position.

Figs. 8, 9 and 10 are enlarged fragmentary views illustrating the action of the iron on the work when said iron first engages the

latter, when it is rocked to roll in the joint, and at substantially the completion of the setting operation, respectively.

Fig. 11 is a sectional view of a heel having a toplift applied thereto, showing the condition of the toplift prior to the edge setting operation.

Fig. 12 is a similar view showing the toplift after the edge setting operation.

Fig. 13 is a similar view showing the completely finished toplift after the buffing and breast trimming operations.

Fig. 14 is a vertical section of the two-part jack shaft and work positioning and clamping devices.

Fig. 15 is a section taken substantially on line 15—15, Fig. 14.

Fig. 16 is a detail section taken substantially on line 16—16, Fig. 14.

Referring to Figs. 11 to 13, A denotes a portion of a Louis heel and B a toplift secured thereto. Fig. 11 shows the toplift B in the condition in which it is applied to the heel, and Fig. 12 said toplift after the operation of the machine thereon, the effect of said operation being to finish the rough edge of said toplift, to roll in the joint a between the heel and toplift, and to form on the latter the bed b, bead c and panel d. In the operation of subsequently finishing the outer or exposed face of the toplift B, the panel portion d is buffed off, leaving the bead c substantially flush with said outer face, as shown in Fig. 13.

Referring to Figs. 1 to 4, 20 denotes the frame of the machine which is suitably designed to provide the necessary bearings, supports and guides for the various parts hereinafter described.

Journalled in the frame 20 is a power shaft 21 having thereon a pulley 22 adapted to receive a belt (not shown) through which power may be applied thereto from any suitable source. Fast on the shaft 21 is a pinion 23 which meshes with a gear 24 rotatably mounted on a stud 25 projecting from the frame 20. The gear 24 meshes with a gear 26 loosely mounted on the main driving shaft 27 journalled in suitable bearings in the frame 20, said gear being attachable to and detachable from said shaft by means of a suitable clutch 28 under the control of a manually operated lever or handle 29. Fast on the shaft 27 is a pinion 30 which meshes with a gear 31 on a cam shaft 32 journalled in suitable bearings in the frame 20.

Journalled respectively in bearings 33 and 34 in the frame 20 are the aligned sections 35 and 36 (see particularly Fig. 14) of a two-part jack shaft, the ends of said sections being spaced from one another and being connected by a yoke 37. The yoke 37 is formed at one end with a hub 38 abutting the bearing 33 and keyed or otherwise fixed to the end of the shaft section 35, and at its opposite end

with a split hub 39 abutting the bearing 34 and secured to the end of the shaft section 36 by a clamping bolt 40 and spline 41, thereby permitting longitudinal adjustment of the shaft section 36 in the hub 39.

- Secured to one end of the main driving shaft 27 is a crank arm 42 (Figs. 1 and 3) having ways to receive a slide 43 adjustable therein by means of an adjusting screw 44.
- 5 Pivoted to the slide 43 is one end of a pitman 45 the opposite end of which is pivoted to a block 46 slidable in a slot 47 in a gear segment 48 pivoted at 49 to the frame 20 and meshing with a pinion 50 secured to the outer end of 15 the section 35 of the jack shaft. The block 46 is normally held in the upper end of the slot 47, to afford a driving connection between the pitman 45 and segment 48, by means of a dog 51 pivoted at 52 to said segment and 20 normally held in operative position by a spring 53 (Figs. 1 and 2). The dog 51 is formed with a foot 4 which depends into the path of movement of a pin 55 projecting from the face of the gear 31 which thereby constitutes a controller for said dog.

It will be seen that with the block 46 locked in its operative position in the slot 47, the jack shaft and work holder will be oscillated from the main driving shaft 27 through the crank 30 42, pitman 45, segment 48, and pinion 50, the amplitude of oscillation being determined, in accordance with the arcuate or circumferential length of the edge of the particular style of toplifts to be operated upon, by adjustment of the slide 43. After one revolution of the gear 31, which may be designed to correspond to any desired number of oscillations of the jack, the foot 4 is engaged by the pin 55, causing the dog 51 to be disengaged 40 from the block 46 leaving the latter free to reciprocate in the slot 47. The jack therefore will remain idle during one complete rotation of the shaft 27, this being the unloading and loading period in the cycle of operations of 45 the machine during which period one completed piece of work is removed from the machine and a new piece inserted. Upon the completion of one rotation of the shaft 27, the pin 55 moves out of engagement with the foot 50 4, permitting the spring 53 to restore the dog 51 to its normal position, thereby again locking the slide 46 to the segment 48, and the oscillation of the jack is resumed or continued.

55 The means for positioning and clamping the work in the jack comprises a toplift rest or plate 56 for engaging the outer face of the toplift B, a breast gauge 7 for engaging the breast of the heel A, a heel seat support 60 58 carrying a detachable positioning plate 59 for engaging the heel seat portion of the heel A, and one or more (preferably two) spurs 6 adapted to be projected into the material of the heel at the heel seat end to secure the same in position.

The toplift plate or rest 56 is carried by the jack shaft section 35 which is formed with an axial bore to receive an attaching stem 61 formed on said plate or rest and engaged at its end by an adjustable abutment 70 screw 62 in threaded engagement with the outer end of the bore in the shaft 35 and having a knurled head 64 by which said screw, and consequently the position of the toplift plate heightwise of the heel, may be adjusted longitudinally of the shaft, the adjustment being fixed by a lock nut 65. Adjustment of the toplift plate or rest 56 positions the toplift heightwise of the heel with reference to the particular iron employed. 80

The breast gauge 7 (Fig. 2) has a shank portion slidably received in the yoke 37 and secured therein in adjusted position by a clamp screw 66. The breast gauge 7 positions the heel horizontally and its adjustment 85 adapts the machine to heels of varying shapes in order that the axis of curvature of the toplift edge may substantially coincide, in the horizontal plane, with the axis of oscillation of the jack, that is to say, the common axis 90 of the shaft sections 35 and 36.

The vertical positioning of the heel, in order to bring said axes substantially into coincidence in the vertical plane, is effected by the sense of touch of the operator with the assistance of the heel seat centering plate 59 which is detachably secured to the heel seat support 58 by spring latches 67 which engage notches in studs 68 formed on the plate. Interchangeable plates 59 corresponding to 95 different widths of heels are provided, a plate being chosen which is of substantially the same or only slightly greater width than the particular heels to be operated upon (see Fig. 14). In inserting a heel, when the opposed clamping devices are drawn apart, as herein-after explained and as indicated in Fig. 5, the operator grasps said heel adjacent the heel seat portion thereof between his thumb and forefinger, places said heel seat portion against the plate 59 with its peripheral edge firmly in engagement therewith, at the same time, by the sense of touch, centering or positioning said heel seat portion in symmetrical relation to the edges of said plate 59, and slides the heel into place on said plate until the breast of the heel engages the stop or gauge 7. It is found in practice that the heel can be very quickly and accurately centered on the plate 59 by the sense of touch, 100 as above described, since said heel and plate are so nearly of equal width. 110

The heel seat support 58 (Figs. 1, 2, 14 and 16) is pivoted for angular adjustment about an axis transverse to the heel upon alined 115 studs 69 carried by a sleeve 70 slidably mounted on a plunger 76 guided for longitudinal movement in an axial bore 77 in the jack shaft section 36. Said heel seat support is provided with a projecting arm 71 movable 120

over a scale 72 (Fig. 2) on a segment 73 carried by the sleeve 70, said arm 71 carrying a clamp screw 74 which cooperates with a slot 75 in said segment, whereby the heel seat support 58 may be secured in any position of angular adjustment. This angular adjustment of the heel seat support 58 adapts the machine to heels having heel seat portions of different inclinations.

10 It will be observed that the positioning of the heel with the plane of the face of the top-lift accurately perpendicular to the axis of relative oscillation of the work and iron, or, in other words, with the axis of curvature of the toplift edge accurately parallel to said axis of oscillation, is effected solely by the engagement of the peripheral edge of the heel seat portion of the heel with the plate 59. The toplift rest or plate 56 plays no essential part 15 in performing this function and may, if desired, be provided with a cushioned or roughened surface to assist in securely clamping the work. By reason of the fact that the heel seat portion of the heel, notwithstanding its 20 usual concavity, has its peripheral edge lying in a plane, this plane can be utilized for the purpose in question to effect a more accurate positioning than is possible by any means cooperating with the toplift, since the 25 latter is of relatively small area in proportion to that circumscribed by the edge of the heel seat, and is relatively more yielding and irregular. It will be understood that the 30 parallelism of the axes of curvature and oscillation is thus obtained by the flatwise engagement of the heel seat edge with the plate 35 59 irrespective of its position thereon, while the substantial coincidence of said axes is obtained by centering said heel seat on said plate 40 and engaging the heel breast with the gauge 7, as above explained.

The sleeve 70 is held against turning on the plunger 76, and its longitudinal sliding movement thereon limited to provide a limited 45 lost-motion connection between said parts, by means of a stud 78 (Figs. 2, 5 and 16) carried by said sleeve and engaging a short groove 79 in said plunger. The sleeve 70 is normally projected toward the toplift rest or 50 plate 56, to the extent permitted by the interposed work and by the engagement of the stud 78 in groove 79, by means of a spring 80 interposed between a shoulder 81 on said sleeve and the adjacent end of the jack shaft 55 section 36.

The spurs 6 are carried by the end of the plunger 76 and project through an opening 82 in the plate 59. The plunger 76 is secured by a pin 83 to the end of a rod 84 longitudinally movable in the bore 77, said plunger being normally projected toward the toplift plate or rest 56 by a spring 85 surrounding the rod 84 and interposed between the plunger 76 and a shoulder 86 formed in the bore 77. The 60 rod 84 is extended to the outer end of the jack 65

shaft section 36 and is provided with a head 87 having a transverse opening or socket 88 to receive the rounded end of one arm of a bell crank 89 (Figs. 1, 2, 4, and 14) pivoted at 90 between ears 91 on the outer end of the jack shaft section 36. The other arm of the bell crank 89 is periodically engaged by an elongated head 92 on a lever 93 pivoted at 94 to the frame 20 and carrying a roller 95 which cooperates with the edge of a cam 96 on the cam shaft 32, said roller being held in engagement with said cam by a spring 97.

With the parts in the positions shown in Figs. 1, 2, 4, 14 and 16, the roller 95 is on the low part of cam 96, the head 93 is disengaged from the bell crank 89, and the springs 85 and 80 operate to project the spurs 6 into the heel and force the sleeve 70 with its attached heel seat support 58 toward the toplift rest 56, thereby clamping the heel in position in the jack. When the roller 95 is engaged by the high portion of the cam 96, the lever 93 is oscillated to cause the head 92 to engage and operate the bell crank 89, thereby drawing the rod 84 outwardly. The first effect of this movement is to withdraw the spurs 6 from the heel, after which the stud 78 is engaged by the end of the groove 79, thereby picking up the sleeve 70 with its attached heel seat support 58 and withdrawing the latter, as shown in Fig. 5, to release the heel and to permit its removal and the insertion of a new heel as above described.

It will be seen that the point to which the spurs 6 and heel seat support 58 are withdrawn with reference to the top-lift rest 56, and the consequent spacing of the heel clamping elements when the heel clamp is released during the loading and unloading operation, are determined by the longitudinal position in the machine of the jackshaft section 36 and the assembly carried thereby. This position can be varied or adjusted, in order to adapt the machine to heels of different heights, by releasing the clamping bolt 40 which secures the hub 39 of the yoke 37 to the jack shaft section 36, moving said shaft section inwardly or outwardly and again tightening said clamping bolt. This adjustment is permitted by the elongated form of the head 92 which enables said head to cooperate with the bell crank 89 in any position of adjustment.

The movable mounting of the sleeve 70 and parts carried thereby, together with the spring 80 which tends normally to project said parts inwardly or toward the work, permits the heel seat support 58 to yield if necessary (due to its angular position) when the heel breast is brought up to the breast gauge 7, but causes the positioning plate 59 to follow the movements of and remain in contact with the heel seat at all times during the insertion of the heel and the closing of the clamping devices, thereby avoiding any

danger of disturbance of the positioning of the heel as determined by said plate.

The iron is mounted in a holder 9 (Figs. 1, 6 and 7) having an arm 100 laterally offset, in the direction away from the outer face of the toplift, from the line of pressure of the iron against the work, said arm 100 being pivoted at 101 between ears 102 on a U-shaped or substantially semi-circular yoke 103. The iron 8 is formed at its outer side with a projection or shoulder 104, and by reason of the above described offset or eccentric pivoting of the iron holder 9, the normal pressure, exerted by means hereinafter described, of the iron against the edge of the toplift is given a component in the direction heightwise of the heel, whereby a portion of said normal pressure is converted into an endwise pressure or thrust of the shoulder 104 against the outer face of the toplift to prevent pouting or cupping. The amount of this endwise component of the iron pressure is definitely but adjustably fixed or determined by a spring 106 interposed between the yoke 103 and an adjustable nut 107 in threaded engagement with a rod 108 upon which said spring is mounted, said rod passing loosely through an opening 109 in said yoke and being secured at its inner end to the holder 9. The spring 106 tends to oppose the swinging of the holder about its pivot 101, and consequently to decrease the endwise component of the pressure by a fixed amount depending upon the resistance of said spring, so that, by adjusting the initial or normal compression of the spring by means of the nut 107, the endwise thrust of the shoulder or projection 104 can be varied in accordance with the requirements of the work, but will remain constant for a given edge pressure until readjusted.

The iron holder 9 is provided with means, preferably in the form of an electric heating unit generally indicated at 110, for heating the same and thereby the iron and may be fitted with a thermometer 111 for indicating the temperature. The iron 8 may, if desired, be backed by a threaded thrust rod 112 for assisting in ejecting the same from the holder when it is necessary to change irons, said thrust rod being preferably composed of copper or similar material to assist in conducting the heat to the iron.

The yoke 103 is pivoted at its ends upon aligned pivots 113 (Figs. 1, 2, 3, 4, 6 and 7) to the curved free end portion of a lever 115 which constitutes the carrier by which the iron 8 is moved toward and from the work, said iron being secured to a shaft 116 journalled in bearings in the frame 20. The axis of the pivots 113 is substantially tangential to the toplift when the iron is in engagement therewith, and substantially coincident with the bead-forming groove 114 (see Figs. 6 and 7) in the iron. In threaded engagement with

the yoke 103 is an adjusting screw 117 having a stem 153 which passes loosely through an opening 118 in the lever 115 and is provided at its outer end with a knurled operating head 119 between which and the lever 115 is interposed a compression spring 120 surrounding said stem. The screw 117 is provided with a fixed collar 121 normally held by the spring 120 in engagement with the inner face of the lever 115, as shown in Fig. 6, said collar constituting a stop for determining the normal position of the yoke 103 and iron 8 about the axis of the pivots 113. The arrangement is such that the normal position of the yoke 103 and the centre line of the iron 8 are substantially parallel to the lever 115, or substantially perpendicular to the axis of oscillation of the jack and heel, this position being, however, capable of slight variation by adjustment of the screw 117. It will be understood that, for any particular work, an iron 8 will be chosen whose bed forming surface 122 (Fig. 8) conforms as nearly as may be to the desired form or curvature of the bed of the finished toplift but that slight discrepancies in this respect may be compensated for as nearly as may be by adjustment of the screw 117 as above described.

The inner end of the adjusting screw 117 is connected by a link 123 with an adjusting screw 124 in threaded engagement with the free end of a lever 125 pivoted at its opposite end at 126 to the frame 20. The link 123 is swivelled in the adjusting screw 124, passing longitudinally therethrough and having at its outer end a head 127, whereby the screw 124 may be turned to adjust the same in the lever 125 without disturbing the connection of the link 123 with the screw 117. The lever 125 is provided intermediate its ends with an arm 128 carrying at its end a cam roller 129 which cooperates with a cam projection 130 formed on the face of the cam 96. The roller 129 is normally urged toward the face of the cam 96 to the extent permitted by the collar 121 by the spring 120 acting through the screw 117, link 123, screw 124, and lever 125. Periodic oscillation of the lever 125 by the cam projection 130 causes the yoke 103, with the iron holder 9 and iron 8, to be rocked from the position shown in Fig. 6 into that shown in Fig. 7, to cause the iron 8 to roll in the joint *a* between the heel and toplift as illustrated in detail in Fig. 9. The lost motion, indicated at 131 in Fig. 1, between the roller 129 and cam 96, and consequently the amplitude of the rocking movement of the iron to roll in the joint, is determined, in accordance with the requirements of the particular work, by the adjustment of the screw 124 in the lever 125. It will be noted that the construction and arrangement are such that the adjustment last referred to is entirely independent of the adjustment of the screw 117 in the yoke 103 so that neither

is affected by the other, although both form parts of the same connection, since the adjustment of the screw 117 in the yoke 103 merely varies the position of said yoke with respect to said screw and does not vary the normal position of the screw itself, which is determined by engagement of the collar 121 with the lever 115.

The lever 115 and the parts carried there-
10 by are normally urged toward the work to apply the requisite pressure of the iron 8 against the edge of the toplift by two springs 132 (Figs. 1 and 2) and 113 (Figs. 1 and 3). The spring 132 is a torsion spring sur-
15 rounding the shaft 116 and secured at one end to the hub 134 of the lever 115. The opposite end of the spring 132 is secured to the hub of a worm wheel 135 angularly ad-
justable on the shaft by a worm 136 jour-
20 nalled in an arm or bracket 137 carried by the inner bearing for the shaft 116, said worm being preferably provided with an operating crank 138. If desired, the hub of
25 the worm wheel 135 may be provided with graduations cooperating with an index mark on the bracket 137 to indicate the adjustment.

The spring 133 is a tension spring connected at one end to a lever 115 adjacent the
30 lower pivot 113 and at its opposite end to one arm of a bell crank 139 (Fig. 3) pivoted at 140 to the frame 20 and having at its opposite end a cam roller 141 which engages the edge of a cam 142 on the cam shaft 32.

35 The spring 132 acts to cause the iron to exert a relatively light or normal pressure upon the work, the amount of which pressure is adjustable by means of the worm mechanism 135, 136. The spring 133, under the
40 control of a bell crank 139, cam roller 141 and cam 142, operates to cause the iron to exert an increased or heavy pressure upon the work at certain times during the operation and to release said pressure when the iron is to be
45 lifted away from the work in order to permit the latter to be introduced and removed.

Pivoted intermediate its ends on the shaft 116 is a lever 143 having at one end a cam roller 144 which engages the edge
50 of a cam 145 on the cam shaft 32. The opposite end of the lever 143 cooperates with an adjustable abutment screw 146 in threaded engagement with a lug 147 on the lever 115. The arrangement is such as to permit a cer-
55 tain amount of lost-motion between the lever 143 and screw 146, which amount may be varied by adjustment of said screw, this lost-motion leaving the lever 115 and parts carried thereby under the influence of the
60 springs 132 and 133 when the cam roller 144 is on the low part of the cam 145, but permitting said lever to engage the screw 146 and lift the iron away from the work when the roller 144 is engaged by the high part of
65 said cam.

A warning bell 148 (Figs. 2 and 3) is prefer-
ably provided, said warning bell being sup-
ported on the base of the frame 20 and hav-
ing a clapper 149 carried by the free end of
a spring arm 150, said arm being secured at its
opposite end to the frame 20 and being en-
gaged intermediate its ends by a projection
151 on a cam 152 on a cam shaft 32. The
arrangement is such as to cause the projection
151 to lift and release the clapper 149 and
cause the same to strike the bell 148 and
thereby give a warning signal just prior to
the interruption of the oscillation of the jack,
70 the opening of the work clamps, and the lift-
ing of the iron from the work, in order that
this operator may, at this time, be in readi-
ness to remove the finished heel and insert
75 another.

In operation, the proper iron 8 having
been inserted into the holder 9, the proper
heel seat plate 59 having been applied to the
holder 58, and the various adjustments above
referred to having been made in accordance
with the requirements of the particular run
or batch of work to be operated upon, the
90 machine is started by operating the clutch
lever or handle 29 to cause the clutch 28 to
connect the gear 26 to the shaft 27. Rotation
of the shaft 27 causes the jack to be oscillated
through the crank 42, pitman 45, segment 48,
95 and pinion 50 so long as the block 46 is locked
in operative position by the dog 51. This os-
cillation is however periodically interrupted
during one rotation of the shaft 27 by en-
gagement of the foot 4 of the dog 51 by the
100 pin 55 on the controller gear 31, causing said
dog to release the block 46 and permit said
block to move idly in the slot 47. During the
same period, the cam 96 acting through the le-
ver 93, bell crank 89, and rod 84, operates to
105 open the work clamp, while the cam 145, act-
ing through the levers 143 and 115, operates
to lift the iron away from the work. These
operations are preceded by a stroke of the
warning bell under the action of the cam 152.
110

The construction shown is so designed that
the complete cycle of operations of the ma-
chine includes five rotations of the shaft 27,
resulting in four complete oscillations or
115 eight arcuate strokes of the jack, followed by
an idle rotation of the shaft 27 during which
the jack remains stationary with the work
clamps released and the iron raised as above
described. It will be obvious however that
the precise number of rotations of the main
shaft, the number of operative strokes, and
the length of the loading and unloading pause
may be varied in different machines to suit
the convenience of the operator or the re-
quirements of the particular class of work
120 for which the machine is designed.

The operator, after starting the machine
by operation of the clutch lever 29, as above
described, awaits the stroke of the warning
bell, immediately after which the oscillation
130

of the jack is stopped, the iron lifted away from the work, and the work clamps released. He thereupon inserts a heel with its attached toplift, the breast of the heel being placed against the gauge 7, as shown in Fig. 5, and the heel being centred on the plate 59 as shown in Fig. 14 by the sense of touch. The speed of operation of the machine is such as to give the operator sufficient time to insert and position the heel during the idle rotation of the shaft 27. Immediately thereafter the cam 96 restores the rod 84 to the influence of the spring 85, causing the spurs 6 to engage and embed themselves in the material of the heel and to clamp the latter, with its attached toplift, against the toplift plate 56. At the same time the cam 142 restores the lever 115 to the influence of the spring 132 and 133, causing the iron to be lowered into engagement with and pressed against the edge of the toplift. Immediately thereafter the pin 155 disengages the foot 54 of the dog 51, causing the latter to lock the block 46 to the segment 48, and the eight operative strokes 25 of the machine are commenced. During the first six strokes the cam roller 141 is in engagement with the high part of the cam 142 tensioning the spring 133 and causing these strokes to be under heavy pressure. During 30 the first stroke the iron is in its normal position, as shown in Figs. 6 and 8, this stroke acting to warm up the wax with which the edge of the toplift has previously been treated and force the same into the joint α . During 35 the second stroke the projection 130 on the cam 96 acts through the lever 125 and link 123 to rock the yoke 113 and iron 198 into the position shown in Figs. 7 and 9 to roll in the joint α . After the completion of the second stroke the iron is restored to normal position and remains therein during the remainder of the cycle of the machine, the next four strokes being applied under heavy pressure with the iron in normal position as shown in 45 Figs. 6 and 10 to mold the edge of the toplift and form the bed, bead and panel thereon. Thereafter the low portion of the cam 142 is brought under the cam roller 141, releasing the tension of the spring 133, and permitting the last two strokes to take place under the light pressure of the spring 132 to further set the edge and polish the same. If desired, these two light strokes may be omitted and the heavy setting strokes depended 50 upon for the desired polishing effect. In the latter event, the tension of the spring 133 may be released only just prior to and during the idle stroke of the machine in order to decrease the pressure and thereby facilitate the lifting of the iron away from the work. At the completion of the next to the last operative stroke, the warning bell is sounded, and upon the completion of the last operative stroke the block 46 is again released from the segment 55 48, the iron lifted away from the work

by the operation of the cam 145, and the work clamp opened by the cam 96, thereby completing the cycle of operations.

Having thus described my invention, I claim:

1. A machine for setting the edges of toplifts attached to heels, said machine including, in combination, an edge setting iron, a jack having means for holding the work and presenting the toplift edgewise to said iron, means for relatively oscillating said iron and jack to cause said iron to travel circumferentially about the edge of the toplift, and means for automatically rocking said iron transversely of said edge about the joint between the toplift and heel. 76 75 80

2. A machine for setting the edges of toplifts attached to heels, said machine including, in combination, an edge setting iron, a jack having means for holding the work and presenting the toplift edgewise to said iron, means for relatively oscillating said iron and jack to cause said iron to travel circumferentially about the edge of the toplift, means for rocking said iron transversely of said edge about the joint between the toplift and heel, and means to adjust the amplitude of such rocking movement. 85 90

3. In an edge setting machine, in combination, an edge setting iron, a jack having means for holding the work and presenting the same edgewise to said iron, means for relatively oscillating said iron and jack to cause said iron to travel circumferentially about the edge of the work, and means for rocking said iron transversely of said edge out of and into normal position, said last-named means being adjustable to vary said normal position and being also independently adjustable to vary the amplitude of the rocking movement. 95 100 105

4. In an edge setting machine, in combination, an edge setting iron, a jack having means for holding the work and presenting the same edgewise to said iron, means for oscillating said jack to cause said iron to travel circumferentially about the edge of the work, a yoke by which said iron is carried, a lever to which said yoke is pivoted to turn about an axis substantially tangential to said edge, a spring cooperating with said lever to press said iron against the work, and means for swinging said yoke upon its pivots to rock said iron transversely of said edge. 110 115

5. In an edge setting machine, in combination, an edge setting iron, a jack having means for holding the work and presenting the same edgewise to said iron, means for oscillating said jack to cause said iron to travel circumferentially about the edge of the work, a yoke by which said iron is carried, a lever to which said yoke is pivoted to turn about an axis substantially tangential to said edge, a spring cooperating with said lever to press said iron against the work, and means 120 125 130

- for swinging said yoke upon its pivots to rock said iron transversely of said edge, said means including a link connected with said yoke, a lever adjustably connected with said 5 link, a cam cooperating with said lever to move said yoke in one direction, a spring for moving said yoke in the opposite direction, and a stop for limiting the movement of said yoke in said last-named direction.
10. 6. In an edge setting machine, in combination, an edge setting iron, a jack having means for holding the work and presenting the same edgewise to said iron, means for oscillating said jack to cause said iron to travel circumferentially about the edge of the work, a yoke by which said iron is carried, a lever to which said yoke is pivoted to turn about an axis substantially tangential to said edge, a 15 spring cooperating with said lever to press said iron against the work, and means for swinging said yoke upon its pivots to rock said iron transversely of said edge out of and into normal position, said last-named means being adjustably connected with said yoke to 20 vary said normal position.
7. In an edge setting machine, in combination, an edge setting iron, a jack having means for holding the work and presenting the same edgewise to said iron, means for 25 relatively oscillating said iron and jack, means for exerting a constant normal pressure between said iron and work, and means for automatically and periodically applying an added pressure.
30. 8. In an edge setting machine, in combination, an edge setting iron, a lever by which said iron is carried, a jack having means for holding the work and presenting the same edgewise to said iron, means for oscillating 35 said jack, an adjustable spring cooperating with said lever for causing said iron to exert a normally constant pressure upon the work, a second spring cooperating with said lever, and a cam and connections for periodically 40 stressing said second spring to increase said pressure.
9. In an edge setting machine, a work-holding jack and mechanism for oscillating the same and for periodically interrupting 45 such oscillation, said mechanism including an oscillating member operatively connected with said jack, a driving shaft having a crank thereon, a pitman connected at one end with said crank, a dog for normally locking the other end of said pitman to said oscillating member, said dog being releasable to permit said pitman to move idly with respect to said member, and a controller driven by said shaft and having means for periodically engaging and releasing said dog and for thereafter disengaging the same to permit it to return to locking position.
50. 10. In an edge setting machine, in combination, an edge setting iron, a jack having means for clamping the work and presenting 55 the same edgewise to said iron, means for relatively oscillating said iron and jack, means for automatically and periodically interrupting such oscillation and thereafter continuing the same, and means operating in timed relation to said interrupting means for 60 opening and closing said work clamping means during the interruptions.
11. In an edge setting machine, in combination, an edge setting iron, a jack having means for clamping the work and presenting the same edgewise to said iron, means for relatively oscillating said iron and jack to cause said iron to travel about the edge of the work, means for automatically and periodically interrupting such oscillation, means for relatively moving said iron and jack to withdraw said iron from the work when said oscillation is interrupted, and means for automatically opening said work clamping means when said iron is withdrawn.
12. In an edge setting machine, in combination, an edge setting iron, a jack having means for holding the work and presenting the same edgewise to said iron, means for applying resilient pressure to said iron, means for relatively oscillating said iron and jack to cause said iron to travel about the edge of the work, means for automatically and periodically interrupting such oscillation, means for withdrawing said iron from the work when said oscillation is interrupted, and means cooperating with said pressure applying means for decreasing the pressure when said iron is withdrawn to facilitate such withdrawal.
13. In a machine for setting the edge of a toplift attached to a heel, in combination, an edge setting iron, a work holding jack, means for relatively oscillating said iron and jack, and means associated with said jack and adapted for cooperation with the flat surface of the rim of the heel seat portion of said heel for angularly positioning a toplift therein with its edge presented to said iron and with the axis of curvature of said edge parallel to and substantially coinciding with the axis of oscillation.
14. In a toplift edge setting machine, in combination, an edge setting iron, a work holding jack, means for relatively oscillating said iron and jack, said jack having means for securing therein a heel with an attached toplift, and means associated with said jack and adapted for cooperation with the flat surface of the rim of the heel seat portion of said heel for angularly positioning said toplift with its face perpendicular to the axis of oscillation.
15. In a toplift edge setting machine, in combination, an edge setting iron, a work holding jack, means for relatively oscillating said iron and jack, said jack having means for securing therein a heel with an attached toplift, and means associated with said jack and adapted for cooperation with the flat surface of the rim of the heel seat portion of said heel for angularly positioning said toplift with its face perpendicular to the axis of oscillation.

- toplift, and means for positioning said toplift with its face perpendicular to the axis of oscillation, said means comprising a member having a plane surface engaged flatwise by the peripheral edge of the heel seat portion of said heel.
16. In a toplift edge setting machine, in combination, an edge setting iron, a jack, means for relatively oscillating said iron and jack, said jack having means for securing therein a heel with an attached toplift, and devices for positioning said heel with the axis of circumferential curvature of said toplift substantially coinciding with the axis of oscillation, said positioning devices including a breast gauge and a centering plate for the heel seat portion of said heel. 70
17. In a toplift edge setting machine, in combination, an edge setting iron, a jack, means for relatively oscillating said iron and jack, said jack having means for securing therein a heel with an attached toplift, and means associated with said jack and adapted for cooperation with the flat surface of the rim of the heel seat portion of said heel for positioning said heel with the axis of circumferential curvature of said toplift substantially coinciding with the axis of oscillation, said last named means including a support for the heel seat portion of said heel and a centering plate detachably secured to said support. 75
18. In a toplift edge setting machine, a work holding jack having means for positioning and clamping therein a heel with an attached toplift, said positioning and clamping means including opposed members for engaging respectively the outer face of said toplift and the heel seat portion of said heel, said last-named member being normally fixed but angularly adjustable about an axis transverse to said heel. 80
19. In a machine of the character described, a jack having means for positioning and clamping therein a heel with an attached toplift, said clamping means including opposed members engaging respectively the heel seat portion of said heel and the outer face of said toplift, and said positioning means including a breast gauge and an angularly disposed, resiliently mounted plate engaging the peripheral edge of said heel seat portion. 105
20. In a toplift edge setting machine, in combination, an edge setting iron, a jack having means for holding a heel with an attached toplift presented edgewise to said iron, and means for automatically pressing a portion of said iron endwise against the outer face of said toplift. 120
21. In a toplift edge setting machine, in combination, an edge setting iron, a jack having means for holding a heel with an attached toplift presented edgewise to said iron, means for automatically pressing a portion of said iron endwise against the outer face of said
- toplift, and means for adjustably fixing the amount of such pressure. 75
22. In a toplift edge setting machine, in combination, an edge setting iron, a jack having means for holding a heel with an attached toplift presented edgewise to said iron, means for pressing said iron against the edge of said toplift, and a mounting for said iron whereby a portion of said pressure is converted into endwise pressure against the outer face of said toplift. 80
23. In a toplift edge setting machine, in combination, an edge setting iron, a jack having means for holding a heel with an attached toplift presented edgewise to said iron, means for pressing said iron against the edge of said toplift, and means whereby a definite but adjustable portion of said pressure is converted into endwise pressure against the outer face of said toplift. 85
24. In a toplift edge setting machine, in combination, an edge setting iron, a jack having means for holding a heel with an attached toplift presented edgewise to said iron, said iron having a projection engaging the outer face of said toplift, a carrier for said iron, means acting upon said carrier for pressing said iron against the edge of said toplift, and a holder for said iron pivoted to said carrier at a point offset from the line of pressure of said iron against the edge of said toplift, whereby a portion of said pressure is converted into an endwise thrust of said projection against the outer face of said toplift. 90
25. In a toplift edge setting machine, in combination, an edge setting iron, a jack having means for holding a heel with an attached toplift presented edgewise to said iron, said iron having a projection engaging the outer face of said toplift, a carrier for said iron, means acting upon said carrier for pressing said iron against the edge of said toplift, a holder for said iron pivoted to said carrier at a point offset from the line of pressure of said iron against the edge of said toplift, whereby a portion of said pressure is converted into an endwise thrust of said projection against the outer face of said toplift, and an adjustable spring for opposing said endwise thrust. 105
26. The herein described method of angularly positioning a toplift attached to a heel with reference to instrumentalities operating on said toplift, which method consists in positioning the plane of the peripheral edge of the heel seat portion of the heel by engaging said edge with a plane surface disposed at a predetermined angle to said instrumentalities. 110
27. The herein described method of positioning a toplift attached to a heel in a machine having relatively rotatable heel clamping and toplift engaging instrumentalities with the face of said toplift perpendicular

to the axis of relative rotation, which method consists in positioning the plane of the peripheral edge of the heel seat portion of the heel by engaging said edge with a plane surface disposed at a predetermined angle to said axis.

28. The herein described method of positioning a toplift attached to a heel in a machine for operating on said toplift, which 10 method includes positioning the plane of the peripheral edge of the heel seat portion of the heel by engaging said edge with a plane surface disposed at an angle to the desired position of the face of said toplift equal to 15 the angle between said face and the plane of the peripheral edge of said heel seat portion.

29. The herein described method of positioning a toplift attached to a heel in a machine for operating on said toplift, which 20 method includes positioning the plane of the peripheral edge of the heel seat portion of the heel by engaging said edge with a plane surface of a width approximately equal to 25 the width of said heel seat portion, and centering said heel seat portion on said surface by the sense of touch.

30. In a machine for setting the edge of a toplift attached to a heel, in combination, 30 an edge setting iron, a work holding jack, means for relatively oscillating said iron and jack, and an angularly fixed member engaged by a portion of the heel seat portion of said heel for angularly positioning said toplift 35 with its face perpendicular to the axis of oscillation.

31. In a machine for setting the edge of a toplift attached to a heel, in combination, an edge setting iron, a work holding jack, 40 means for relatively oscillating said iron and jack, and an angularly fixed member having a plane surface engaged flatwise by the peripheral edge of the heel seat portion of said heel for angularly positioning said toplift 45 with its face perpendicular to the axis of oscillation.

In testimony whereof I affix my signature.
MERTON W. HOWARD.
